(57) CLAIM

We claim the ornamental design for a microwave oven, as shown and described.

DESCRIPTION

FIG. 1 is a front and top perspective view of a microwave oven of the present invention;

FIG. 2 is a top view thereof;

FIG. 3 is a front view thereof;

FIG. 4 is a bottom view thereof;

FIG. 5 is a first side view thereof; and,

FIG. 6 is a second side view thereof.

The broken lines shown represent unclaimed subject matter and form no part of the claimed design.
